UNITED STATES PATENT OFFICE.

MELLE E. LOWMAN, OF SYRACUSE, NEW YORK, ASSIGNOR TO SCHMEER'S PAPER BOX COMPANY, OF SYRACUSE, NEW YORK, A CORPORATION OF NEW YORK.

CARTON.

Application filed May 18, 1923. Serial No. 639,846.

This invention relates to improvements in cartons, designed especially for packing "brick" ice-cream, butter and other products, and has for its object to provide a single blank from which both the body and cover of the carton may be formed by a few simple folding operations. A further object is to provide a blank consisting of a sheet of foldable material, wherein one end comprises the several portions from which the body of the carton may be formed; while the opposite end of the blank comprises the several parts of the cover, and wherein the medial portion of the blank comprises the corresponding ends of the body and cover, and serves to properly space and integrally join said parts. A further object is to provide suitable locking flaps or lugs, for facilitating the assembling of the body and cover. A further object is to provide means for effecting the "knock-down" assembly of the blank for shipment and storage. And a further object is to generally improve, simplify and lessen the time, labor and cost of constructing and assembling cartons of this class.

I attain these objects by the means set forth in the detailed description which follows, and as illustrated by the accompanying drawings, in which—

Figure 1 is a plan view of the blank from which the combined body and cover of the carton may be formed. Fig. 2 is a top-plan view; showing the body and cover partially assembled. Fig. 3 is a front end elevation of the completely assembled carton. Fig. 4 is a side elevation of the device shown in Fig. 2. Fig. 5 is a similar view; showing the ends of the body and cover folded and locked. Fig. 6 is a side elevation of the carton shown in Fig. 3. Fig. 7 is an enlarged fragmentary section; showing the means for locking one of the cover ends. Fig. 8 is a similar view; showing the means for locking the front end of the body. Fig. 9 is a view showing the "knock-down" carton with the body and cover extended. And Fig. 10 is a view showing the carton ready for shipment and storage.

In the drawings, 2 represents the one-part blank from which the complete carton is formed. 3 is the bottom, 4 is the outer front end portion, and 5—5' are the opposite side portions of the body A of the carton, the said end and side portions being

foldable by means of similar creases or scorings, indicated by the dotted lines 4' and 5^a—5^b. The side portions 5—5' are integrally joined to corresponding end flaps 6—6' and 7—7', the said flaps being foldable inwardly respectively for overlapping each other (see Fig. 2), by means of common transverse creases 4' and 7^a. The end flaps 6—6' are provided with similar slots 6^a, which register with each other when the said flaps are folded (see Figs. 4, 5 and 8), and the end portion 4 of the body is provided with an extension 4^a, whose free end margin is formed with a tongue 4^b, which may be woven through the slots 6^a, for locking the parts 4, 4^a, and 6—6' together when the said extension is folded inwardly upon the end 4. The extension 4^a is folded first along a crease 4^c, for positioning the tongue 4^b over the slots 6^a, after which the extension is again folded along a crease 4^d for effecting the locking, as described. To make the locking of the end 4 more effective, the extension 4^a is provided with guard lugs 4^e, which are disposed at the opposite sides of the tongue 4^b, and bear against the flap 6' when the folding operation is completed, as shown in Fig. 8. The flaps 7—7' when folded on the crease 7^a overlap each other, as shown in Fig. 2, and when so positioned said flaps are interlocked in a well-known manner by means of similar oppositely facing lugs 7^b—7^c (see Figs. 1 and 2). The flaps 7—7' co-operate with the flaps 6—6' for holding the sides 5—5' parallel to each other and perpendicular to the bottom 3. Each of the sides 5—5' is provided with an oblique crease 5^e, for facilitating the "knock-down" arrangement of the partially assembled body, as shown in Figs. 9 and 10.

The right-end portion of the blank 2, comprises the several parts of the cover B, which consist of the top 8, and the outer end portion 9, the latter being foldable towards the top, by means of a transverse crease 8'. The end 9 is provided with a similar extension 9', whose free end margin is formed with a tongue 9^a, which is disposed between guard-lugs 9^b. 10—10' represent the sides of the cover B, which are foldable towards each other, by means of longitudinal creases 10^a. To the outer ends of the sides 10 are joined end flaps 10^b—10^c, which are also foldable on the crease 8', the said flaps being severed from the end portion 9, as in-

dicated by the solid lines 10^a. The flaps 10^b—10^c are provided with similar slots 10^e, which are arranged to register when the flaps are over-lapped, as shown in Figs. 3, 5 and 7, and the end 9 and the flaps 10^b—10^c are suitably locked by passing the tongue 9^a through the said slots, as best seen in Figs. 5 and 7. For this purpose, the extension 9' is foldable first along a crease 9^c, for positioning the tongue 9^a over the slots 10^e, after which the end 9' is finally folded along a parallel crease 9^d, for passing the tongue through the said slots. The sides 10—10' are provided with oblique creases 10^f, for facilitating the "knock-down" arrangement of the cap B, as shown in Figs. 9 and 10. The free ends of the sides 10—10' are preferably cut angular, as shown, for obviating interference with adjacent parts, as well as for improving the appearance of the carton, as shown in Fig. 6.

The body A and cap B are integrally joined by a medial portion 12 of the blank, which is disposed between parallel transverse scorings 7^a—12', by means of which the portion 12 may be folded upwardly (at the crease 7^a) for forming the inner end of the body, as well as the corresponding end of the cover, which over-laps and incloses the end flaps 7—7'. After the medial portion 12 is folded, as described, the cover B may be folded towards the body A, by means of the scoring 12', for closing the open top of the body, as shown in Figs. 3 and 6.

In order to economize in storage space, as well as to facilitate the final assembling of the carton, by the vendors of ice-cream, and the like, skilled operators at the factory generally perform the greater part of the folding operations, as shown in Figs. 9 and 10. To accomplish this work, the operator first folds the blank 2 substantially as shown in Figs. 2, 4 and 5, except that the inner flaps 7—7' are left unfolded, as shown in Figs. 1, 9 and 10. After the end portions 4 and 9 are folded and locked to the end flaps 6—6' and 10^b—10^c (see Figs. 5, 7 and 8) the operator folds the body and cap respectively along the broken lines or creases 5^c and 10^f, for forming the extended "knock-down" device, shown in Fig. 9. This latter operation may then be followed by folding the cover B towards the body A, by means of the crease 8', for forming the more compact "knock-down" device, shown in Fig. 10.

The provision of the one-part blank 2, eliminates the cost and use of one die, as well as the time and labor required to operate said die, and owing to the novel design of the said blank, I am able to effect a considerable saving of material, as well as greatly reducing the labor and cost of manufacturing and assembling the blanks ready for shipment and use.

Having thus described my invention, what I claim, is—

1. In a folding paper box, a blank comprising a body and a top connected together, said body being transversely and longitudinally scored to provide bottom, front and side walls, the forward ends of said front and side walls having flaps adapted to overlap and formed with parts adapted to interlock to support the front wall of the body and flaps carried by the rear ends of said side walls and having interlocking parts to support said walls in an upright position; a top transversely and longitudinally scored to provide side and front walls, locking flaps carried by the ends of said side and front walls adapted to overlap and interlock to support the front wall of said top and a strip connecting the body and top together and forming the rear wall of said body.

2. In a folding paper box, a blank comprising a body and a top connected together, said body being transversely and longitudinally scored to provide bottom, front and side walls, the forward ends of said front and side walls having flaps adapted to overlap and formed with parts adapted to interlock to support the front wall of the body and flaps carried by the rear ends of said side walls and having interlocking parts to support said walls in an upright position; a top transversely and longitudinally scored to provide side and front walls, locking flaps carried by the ends of said side and front walls adapted to overlap and interlock to support the front wall of said top and strip connecting the body and top together and forming the rear wall of said body, the flap carried by the front wall of the body and the flap carried by the front wall of the top being transversely scored to facilitate interlocking of the front wall flaps with the flaps carried by the side walls.

In testimony whereof I affix my signature.

MELLE E. LOWMAN.
